UNITED STATES PATENT OFFICE

2,435,131

SHOE WITH MOISTURE ABSORBING MEANS

Joseph A. Desbiens, Fall River, Mass.

Application May 24, 1946, Serial No. 671,995

3 Claims. (Cl. 36—3)

1

This invention relates to improvements in shoes having moisture absorbing means.

An object of the invention is to provide an improved shoe construction which will provide means for receiving a desiccant such as silica gel for absorbing perspiration from the feet.

Another object of the invention is to provide an improved shoe construction including an upper and outsole with an insole placed above said outsole forming a space wherein a desiccant such as silica gel may be received to absorb perspiration from the foot to keep the same in a dry and healthy condition.

A further object of the invention is to provide an improved shoe construction having a compartment with a removable closure positioned between the outsole and a perforated insole, wherein a desiccant such as silica gel may be received and replenished when necessary, to absorb moisture and perspiration from the foot to maintain the same dry, thereby preventing many foot troubles, of which "athlete's foot" is a main one.

Another object of the invention is to provide an improved shoe construction including a plastic compartment in which a desiccant such as silica gel may be received, said shoe being highly beneficial and useful when worn, and relatively inexpensive to manufacture and produce.

Other objects will appear as the description proceeds.

In the accompanying drawings which form a part of this application,

Figure 1 is a side elevation of a shoe formed in accordance with the instant invention, the same being partly broken away and in section to show the inner construction thereof;

Figure 2 is a longitudinal sectional view taken on the line 2—2 of Figure 1, and

Figure 3 is a rear elevation of the improved shoe.

Like characters of reference are used throughout the following specification and the accompanying drawings to designate corresponding parts.

In carrying out the invention, there is provided a shoe having an upper generally denoted by the reference numeral 1, having an outsole 2 of leather or other suitable material, and a heel 3

2

attached thereto either formed of leather or rubber.

A strong and flexible plastic base liner 4 is secured to the outsole 2 to lie in contact with the upper surface thereof, and supports the thickened welt 5 of plastic which extends inwardly about the periphery of the outsole, and is secured to said outsole 2 and base liner 4 and to the shoe upper 1, in the usual manner.

An inner sole 6 is formed of a strong and flexible plastic and is provided with many apertures or vents 7 extending therethrough. It will be seen that there is a space or compartment provided between the inner sole 6 and the base liner 4 in which a desiccant 8 such as silica gel may be received, the same being deposited in said space or receptacle through a filling opening 9 at the rear of the shoe when the plug 10 is removed from said opening 9. When the space is completely filled with the crystals of silica gel 8, the plug 10 will be replaced in the opening 9, and will be held therein by the oppositely disposed friction catches 11.

It will be understood that the silica gel crystals 8 may be replenished whenever necessary to insure the total absorption of moisture and perspiration from the feet.

It is a well known fact that dry feet are usually more healthy and are less liable to be affected by the many foot troubles incident to damp perspiring feet, hence with the use of the improved shoes hereinbefore described, any dampness or perspiration will be absorbed by the desiccant or silica gel.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. In a shoe including an upper, an outsole and a heel attached thereto, spaced plastic layers between said upper and outsole, a plastic welt 50 between said spaced plastic layers, and a desic-

cant in said space formed by said plastic layers and plastic welt.

2. The subject matter as claimed in claim 1, and said upper plastic layers being apertured to permit moisture to pass therethrough to be absorbed by the desiccant.

3. The subject matter as claimed in claim 1, said upper plastic layer being apertured to permit moisture to pass therethrough to be absorbed by the desiccant, and means for replenishing the desiccant including a filling opening between said plastic layers and a lockable closure plug therefor.

JOSEPH A. DESBIENS.
